UNITED STATES PATENT OFFICE.

GEORGE P. MILLER, OF GOVANS, MARYLAND.

BOTTLE-LABELING MACHINE.

1,209,191.

Specification of Letters Patent. Patented Dec. 19, 1916.

Application filed February 18, 1915. Serial No. 9,161.

To all whom it may concern:

Be it known that I, GEORGE P. MILLER, a citizen of the United States, residing at Govans, near Baltimore, State of Maryland, have invented certain new and useful Improvements in Bottle-Labeling Machines, of which the following is a specification.

This invention relates to labeling machines.

One object is to provide a bottle labeling machine embodying means whereby the bottles may be fed intermittently through a machine, and effectively labeled during the intervals between the feeding steps.

Another object is to provide a bottle labeling machine to operate in unison with a bottle filling machine of the intermittent or step by step variety, or which may perform its functions separately from the bottle filling machine.

Another object is to provide a bottle labeling machine wherein a plurality of bottles may be fed simultaneously step by step and all operated upon simultaneously during the intervals between the feeding steps, so that as the final step in the labeling operation is being performed on one bottle, the other bottles are being treated separately in the application of labels thereto for said final step in the labeling operation.

Another object resides in the provision of a bottle labeling machine embodying, among other characteristics, means whereby bottles which are being fed through a machine for filling purposes intermittently or step by step, are acted upon during intervals of rest in the intermittent or step by step feed of the bottles for the purpose of applying labels thereto.

Another object is to provide a bottle labeling machine in which a plurality of bottles may be fed intermittently into co-operative relation with the labeling machine and in which, while the final labeling step is being performed on one bottle, another bottle is being supplied with adhesive substance, and a bottle which has been supplied with adhesive substance is having a label applied thereto, and in which, where a bottle which has been supplied with adhesive substance and a label is having its label subjected to moisture, so that at all times each bottle of each plurality thereof is being acted upon to carry out the labeling operation.

A still further object is to provide a bottle labeling machine in which a plurality of

labels may be fed intermittently into co-operative relation with the labeling machine, and in which one bottle may be supplied with an adhesive substance, another bottle at the same time supplied with a label to which an adhesive substance was applied during a previous operation, and in which the label of another bottle which has been labeled in a prior operation is subjected to moisture, and in which a label which has been applied over the adhesive material on one bottle and moistened in a previous operation is subjected to a drying medium.

A still further object is to provide a bottle labeling machine with a label magazine and a label affixing device which co-operates with the magazine in combination with means to create alternately a vacuum or suction and a pressure whereby the label affixing device may take one label at a time from the magazine under the influence of vacuum or suction and apply the label to a bottle which has been supplied on one wall thereof with an adhesive substance, and from which label affixing device the label may be released by air pressure passed through the label affixing device.

A still further object is to provide a bottle labeling machine embodying means whereby the bottles may be fed intermittently through a machine and effectively labeled during the intervals of rest between the feeding steps, without danger of breaking the bottles or cupping or curling the labels, and without the necessity of subsequently wiping adhesive substance from the bottles or labels, and without the necessity of placing the labeled bottles in a drying room for drying purposes.

With these and other objects in view the invention consists of the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or sacrificing any of the advantages of the invention.

In the drawings:—Figure 1 is a front elevation of one embodiment of my invention. Fig. 2 is a top plan view. Fig. 3 is a transverse vertical sectional view on the line 3—3 of Fig. 1. Fig. 4 is a vertical transverse sec-

tional view on the line 4—4 of Fig. 1. Fig. 5 is a vertical transverse sectional view on the line 5—5 of Fig. 1. Fig. 6 is a detail vertical fragmentary sectional view through the lower or mouth end of either the adhesive or moistening magazine. Fig. 7 is a detail perspective view of the moisture applying arm pad, which is the same character of pad as that carried by the adhesive applying arm, except that the latter has not the air aperture therein. Fig. 8 is a detail perspective view, partly in section, showing the label applying arm, parts, including its pad, being separated. Fig. 9 is a detail sectional view through the pressure and suction pipe, illustrating the relief valve thereof. Fig. 10 is a detail sectional view of the diaphragm pump. Fig. 11 is a detail sectional view of the heating means for drying the labels on the bottles.

In carrying the present invention into practice, it will be understood that it is combined with a machine designed for filling, labeling, and corking bottles. The corking machine is embodied in a separate application, as is also the machine for filling the bottles. It is deemed unnecessary to illustrate and describe in detail in this case either the corking mechanism or the filling part of the machine, except in so far as is necessary to show the present labeling device coupled up with the filling machine. To these ends just alluded to, there is illustrated in the accompanying drawings a portion 20 of the framework of the filling machine, on which latter is supported in any suitable manner a shelf 21 over which the bottle *a*, *b*, *c*, *d*, *e*, and *f* are fed, after they have been filled by the filling mechanism, (not shown) by means of pockets 22, secured in any suitable manner to a suitable chain belt or other feeding means 23, operated intermittently in any suitable manner.

The pockets 22 are preferably open at their upper and lower ends so that the bottoms of the bottles slide along the shelf 21. These pockets are preferably detachably connected to the feeding means 23 in any suitable manner, so that pockets of various sizes may be secured to the feeding means, and it will be understood that they may be of any form other than that herein illustrated.

By virtue of the intermittent travel of the feeding means 23 all of the bottles carried in the pockets come to rest momentarily and at the moment they come to rest, my improved labeling mechanism comes into play.

At each end of the framework 20 there is a bracket 25 and a stop strip 26 connects the outer ends of these brackets. The brackets may be supported by arms 27 and 28, or in other framework, in any suitable man-

ner, bolts 29 being shown as piercing the frame 20 and the angular extensions 30 of the arms 27, bolts 31 being shown as passing through the arms 28 and the brackets 25.

Uprights 32 and 33 are supported on the brackets 25 in any suitable manner, and in the upper ends of these uprights 32 and 33 is journaled a rock shaft 34. An upright 35 is secured in any suitable manner on the framework 20 in the upper end of which is journaled a stub shaft 36. A beam 37 connects the stub shaft 36 and the front elongated shaft 34 and braces the uprights.

A glue or other adhesive substance magazine A, a labeling magazine B, a water or other moistening medium magazine C, and a heating device D, the latter for drying purposes, are arranged in spaced relation, and each magazine has a bearing 38 by which it is keyed to and swings with the rock shaft 34 mounted in the aforesaid front standards 32 and 33. These magazines and the heating device are of particular construction and will be described in detail hereinafter. They are all connected together by means of a suitable connection 39, so that they may be swung together into and out of operative feeding positions.

A common means is provided to swing the magazines A, B, and C and the heating device D into and out of operative positions, and this particular means may be varied. As shown, there is mounted on the aforesaid stub shaft 36 a disk 40, to which a cam operated lever 41 may be eccentrically connected at 42. This lever 41 is connected at its lower end by a cam mechanism 22' to the drive shaft 42, which latter operates the bottle feeding means 23 intermittently through the gear connection 23' and shaft 23^a. A pitman 43 is eccentrically connected at 44 to the disk 40 at one end, and at its opposite end pivotally connected at 45 to an arm 46 keyed to the aforesaid rock shaft 34 intermediate the ends of the latter and provided with a link 48 pivotally connected at 49 to a link 50 pivoted at 51 on the aforesaid beam 37.

Coöperating with the magazines A, B, and C and the heating device D are swinging arms E, F, G, and H respectively, which are designed to contact alternately with the respective magazines and heating device and with the respective bottles, the bottles being in coöperative relation to the magazines and the heating device when the latter are in normal vertical positions and in coöperative relation with the bottles when the magazines are in inoperative or inclined positions.

The magazines and the heating device must be swung to their outward or inoperative positions to permit the swinging arms E, F, G, and H to swing to coöperative relation with the bottles. With this thought in mind the swinging arms E, F,

G, and H are each rotatively connected to a shaft 52, journaled in suitable bearings on the brackets 25. This shaft 52 is hollow to provide an air duct from which air 5 may be sucked and through which it may be forced by means of a suitable pump I, which is preferably, although not necessarily, in the form of a diaphragm pump, including a diaphragm chamber 53 and a dia- 10 phragm 54, operable by a shaft 55 connected up with any suitable mechanism (not shown) for actuating the same. Said shaft 55 may have a guiding stem 55' if desired. The hollow shaft 52 may be provided with 15 a suitable air relief valve 56.

The swinging arms F, G and H are connected up with the hollow shaft by means of suitable flexible tubular connections 57, 58 and 59 respectively. A stub shaft 60 20 is journaled in any suitable manner in the arms 27 and 28 or any other suitable part of the framework of the machine, and on this stub shaft 60 is mounted an arm 61 carrying a segmental gear 62 adapted to 25 mesh with a gear 63 on the hollow shaft 52. This arm 61 has an extension 64 projecting over the main drive shaft 42 into coöperative relation with the cam mechanism 22', so as to rock the segmental gear 62 in oppo- 30 site directions, which, by virtue of the meshing relation of the segmental gear 62 with the gear 63 of the shaft 52, causes said shaft to rock and in its rocking movement swing the arms E, F, G, and H, which 35 coöperate with the magazines A, B, C, and the heating device D respectively into and out of coöperative relation with the respective bottles.

As has been stated, the swinging arms E, 40 F, G and H cannot be swung to coöperative relation with the bottles until the magazines A, B, and C and the heating device D have been swung outward to inoperative positions. Nor can the magazines and the 45 heating device be swung outwardly until the swinging arms have been lowered slightly from tight engagement with the lower ends of the same. Thereafter, just as the bottles come to rest during the intermittent feed 50 thereof, the notch 64' in the arm extension 64 receives the cam lug 64^a and causes the segmental gear 62 to rock slightly. This motion lowers the arms and renders the magazines and the heating device free to 55 swing outwardly, because the outer ends of the arms are lowered from tight engagement with the lower ends of the magazines and the heating device. The continued operation of the cam mechanism 22' causes the 60 lever 41 to move downwardly and turn the disk 40, which causes a rearward movement of the pitman connection 43. This pitman connection 43, in its rearward movement, draws the arm 46 rearwardly of the machine, causing rocking movement of the 65

shaft 34 and a consequent outward swing of the magazines and the heating device. Upon the outward swing of the magazines and the heating device, the continued rotation of the cam mechanism 22' causes the 70 cam arm 64^c, disposed under the arm extension 64, to raise the latter, lifting the recess 64' from over the cam lug 64^a and rocking the segmental gear 62, causing the arms E, F, G and H to swing into contact with the re- 75 spective bottles. The connections between the cam lever 41 and the arm extensions 64 with the main drive shaft of the filling mechanism are so made and timed that prior to movement of the bottle feeding 80 means, after the interval of rest incident to the intermittent feed, the magazines and the heating device swinging inwardly and the swinging arms E, F, G and H swing downwardly to their normal positions and 85 into tight engagement with the lower ends of the magazines and the heating device. The label magazine has a stop g to engage the stop strip 26 to limit inward movement of the magazines and the heating device. 90

The adhesive magazine A is preferably of tubular formation, carrying at its lower end a collar 66 having screw threaded connection 67 with the body of the magazine. This collar 66 is preferably composed of 95 metal and has screw threaded sockets 68. Against this collar is disposed an annular plate 69 which is preferably of steel and slotted to permit the adhesive material to pass through the same. Adjacent this 100 slotted annular plate 69 is a finely perforated metal plate 70, through which the adhesive material flows onto a linen or other piece of material 71. A metallic plate 72 is disposed below the linen material 71 and the elements 69, 70, 71 and 72 are clamped between the plate 72 and the collar 66 by means of suitable screw threaded fastenings 73 having working fit in the aforesaid screw threaded sockets 68 of the collar 66. 110

The plate 72 is provided with an open mouth 74 adapted to take or receive tightly the pad 75 of the swinging adhesive applying arm E, and through which open mouth 74 the adhesive substance is applied to said pad 75 of the swinging arm E. The pad 75 may be secured to the head 75' of the arm E by fastenings, and the flow of adhesive material may be regulated by means of a suitable valve 76. 115

The swinging adhesive applying arm pad 75 is preferably convex in cross section and composed preferably of rubber made up after the fashion of the pad 103 of the arm G, having a marginal rib 77 and spaced 120 longitudinal ribs 78. It is formed convex so as to take a supply of adhesive material from the magazine A of an area slightly less than the width of the label B' to be later applied to the bottle, with the result 125 130

that even though the rubber pad expands or spreads in its contact with the bottle, the adhesive substance will not be wasted or forced out from between the bottle and the label and subsequently gum the lithographed face of the label.

It will thus be understood that the pad 75, when in its normal position under the adhesive magazine A, is thrown downwardly slightly prior to the swinging arm E and its pad is then swung to co-operative relation with the bottle, the pad carrying with it the adhesive material to be applied to a paneled or other face of the bottle b.

15 To prevent breakage of bottles, it is preferred that the swinging arm E has not only a soft yieldable pad, but also has a flexible joint 80, which is normally maintained broken by means of a suitable spring 20 81 with the result that the pad 75 yieldably engages the bottle. As a matter of fact, it may be stated at this point that each of the swinging arms E, F, G and H is formed alike as regards this breakable joint, all for 25 the same purpose of providing for yieldable pressure of the pads of the swinging arms on the bottles. These breakable spring tensioned joints have also another function, in that they provide for a yieldable engagement of all of the pads and the heating device arm with the mouths of the respective magazines and the heating device, so as to provide for proper connection of these parts when in co-operative relation.

30 35 The label magazine B is preferably rectangular in cross section, and of a size to permit free movement of the labels therein. At its lower end it has a plurality of yieldable fingers 82, which are designed to prevent accidental displacement of the labels through the discharge end or mouth of the magazine. The labels are preferably disposed in the magazine B with their lithographed faces downward, and if desired, a 40 45 weighted follower 83 may be disposed on top of the labels.

A water chamber 84 is preferably secured to the magazine B by means of suitable brackets 85, and slideable in the latter. This 50 water chamber carries at its lower end a wiper 86 of fabric or other suitable material, and is caused to slide in the brackets 85 by means of a pitman connection 87 pivotally connected to an arm 88 projecting from the aforesaid link 50. This water chamber 84 is supplied with water, preferably from the moistening magazine C, by means of a suitable flexible or other pipe connection 89. The chamber 84 gradually rises to clear the 55 60 stop strip 26 as the label magazine B moves to its outer inclined position and lowers as the label magazine B is thrown to its inward vertical position so as to wipe over the pad 90 of the swinging label affixing arm F and slightly moisten the same to

facilitate taking labels from the label magazine.

The swinging label affixing arm F has a valve chamber 91 into which leads the aforesaid flexible pipe connection 57 from the hollow shaft 52. The pad 90 of this swinging element F has a metallic head plate 93 provided with a slot 94. On this slotted plate 93 is disposed a rubber pad 90, which has a marginal rib 95 and a rib 96 connecting the marginal rib 95 intermediate the ends of the pad and dividing the pad into two sections, so that if one section did not effectively hold the label on the pad, it would not interfere with holding action on the label by the other section. On opposite sides of the rib 96 are short rods 97, arranged in spaced relation and whose ends are not connected with the sides of the pad. Between the ribs 97 are formed apertures 98 which have communication with the valve chamber 91 in the arm F through the slot 94 in the head plate 93, whereby, incident to suction through the hollow shaft 52, the tube 57, and the valve chamber 91, one label at a time may be sucked out of the mouth of the label magazine, the pad 90 being notched at its sides and ends so as to take the aforesaid spring elements 82 arranged at the mouth of the label magazine. The suction through the hollow shaft 52, the pipe 57, and the valve chamber 91 holds the extracted label on the pad 90, so that as the swinging arm F moves upwardly it may retain the label and apply it to the bottle c, to which, it will be understood, the preceding swinging arm E has applied the adhesive material. As the label is applied to the adhesive material on the bottle, the pump I is operated in the opposite direction and causes air pressure to release the label from the pad 90, leaving the label on the bottle with its lithographed face outward. The ribs and intervening spaces between the ribs on the working face of the pad 90 prevent wrinkling or cupping of the labels.

It will now be understood that by the time a bottle reaches the point opposite the moistening magazine C, it has been supplied with adhesive material and also with a label, and now the outer face of the label is moistened as a means to prevent cupping or curling of the label. The moistening medium is preferably water and is carried in the water magazine C and supplied through the lower end or mouth of the magazine C to the swinging arm G in the same manner that the adhesive material is supplied by the magazine A to the swinging arm E. The lower end or mouth of the magazine C is formed substantially like the lower end or mouth of the adhesive magazine A.

The swinging moisture arm G is provided with a cavity forming a valve chamber 99, with which connects the aforesaid tube 58

leading from the hollow shaft 52. The ball valve 100 is disposed in the valve chamber 99 to prevent the flow of water through the tube 57 into the hollow shaft.

5 The head 101 of the moisture applying arm is provided with an opening 102, and on this head 101 is secured in any suitable manner a pad 103, preferably of the same form as the pad 91 carried by the swinging adhesive applying arm E, the only difference residing in the pad 103 having an air hole 104 through which air under pressure from the pump I may pass from the chamber 99 to and through the opening 102 when the 10 pad 103 is thrown into contact with the label, to facilitate the application of the moistening medium to the label.

When the moisture applying arm G returns to its horizontal position, the ball 20 valve 100 closes the communication between said chamber and the hollow pipe 52 to prevent moisture or water from finding its way from the chamber 99 through the connection 57 into the hollow shaft 52, and yet permit 25 unseating of the valve 100, so that moisture or water in said chamber 99 may be forced under pressure by the pump I into and through the pad 102 to effectively moisten the label which has been applied to the bottle 30 by virtue of the steps hereinbefore described. Moistening of the label in this way prevents curling, wrinkling, or cupping of the label.

When a bottle has reached a point opposite 35 the heating device D, it will be understood that it has had adhesive material applied thereto and also a label which has been moistened.

The part D of the heating device is 40 low and has an air inlet opening D' and encloses a resistance coil 105 which is connected up in any suitable manner with an electric light current socket (not shown). The lower end of the part D is flared to provide 45 a mouth 106 adapted to receive the head 107 of the swinging arm H. The part D has an electric terminal 108 at its lower end and insulated therefrom and adapted to be received by the terminal composed of the 50 spaced elements 109, carried by and insulated from the swinging arm H, when the swinging arm H and the part D of the heating device come into coöperative relation. The head 107 of the arm H has apertures 55 110 which lead into a chamber 111 formed at the outer end of the swinging arm H, and in which is located a resistance coil 112, so that when the swinging arm H is brought into coöperative relation with the part D of 60 the electric heating device, designed for drying purposes, the heat from the resistance coils 105 and 112 is drawn by suction through the shaft 52 and the pipe 59 into a chamber 113 in the arm H.

65 At the breakable joint connection in the

arm H there is located a valve 114 which is opened when the breakable joint is closed, and which is closed when the arm is in coöperative relation with the part D, so that the heated air passing into the chamber 113 70 passes through the valve 114 into the chamber 115 of the arm H, where it is trapped.

When the part D of the heating device swings away from the arm H, the breakable joint in the latter spreads or separates, with 75 the result that the valve 114 closes, trapping the heated air in the chamber 115 of the arm. When the arm E swings to its vertical position in contact with the label on the bottle, the pump I is causing a pressure 80 to flow through the hollow shaft 52 and by virtue of the connection 59 between said hollow shaft 52 and the chamber 115, the heated air trapped in the chamber 115 is forced through the open valve 114 and 85 through the chambers 113 and 111 and through the apertures 110 into contact with the moistened label on the bottle to dry the latter, the breakable joint being closed when the head 107 of the arm H engages the label, 90 thereby opening said valve 114 and permitting the pressure to force the heated air against the label on the respective bottle.

It will now be understood that if my improved labeling machine is applied to a 95 bottle filling machine, that the bottles are fed preferably step by step by the feeding means 23 over the shelf 21 and that this feeding means preferably includes pockets in which the bottles are fed in spaced relation to one another, one bottle in each pocket. It will be further understood that the bottles are operated upon during intervals of rest 100 between the step movements of the feeding means. Any other suitable supporting 105 means for the bottles may be employed, and objects other than bottles may be labeled by my improved machine.

For purposes of illustration, there is shown a plurality of six bottles a, b, c, d, e 110 and f. It will be assumed that the bottle f has been labeled and that the bottle a has not yet come into coöperative relation with the labeling machine, and that the bottles b, c, d, and e are in coöperative relation to 115 the labeling machine and the feeding means is at rest. At this point of rest in the feeding means the bottle b will be supplied with adhesive material by the adhesive applying arm E, the bottle c, which has been supplied 120 with adhesive material during the last interval of rest of the feeding means, being in position to receive a label applied thereto by the label applying arm F. The bottle d has been supplied with adhesive material and 125 also with a label by the respective arms E and F, and is now at a point of rest for a third time opposite the labeling machine and in position to be moistened and is moistened by the moisture applying arm G at the 130

same time that the adhesive material and a label are applied to the respective bottles *b* and *c*. The bottle which has had adhesive material and a label applied thereto and which has been moistened by the moistening arm *G* in successive order during three prior intervals of rest of the feeding means, is, on the fourth time of rest of the feeding means, brought into position for coöperation with the heating device *D*, when the heated air trapped in the chamber 115 of the arm *H* is forced under pressure through the apertures 110 in the head 107 of the arm *H* against the label, effectually drying the label and obviating the necessity of taking the labeled bottle to a drying room.

With the explanation of operation immediately foregoing, when considered in connection with the foregoing detailed description and operation of the various parts of the machine, it is thought entirely unnecessary to enter further into detail with regard to the operation of the machine.

What is claimed is:—

25 1. In a bottle labeling machine, a shelf for supporting a plurality of bottles, means mounted above the shelf to drag the bottles in upright position along on the shelf, step by step, means for applying adhesive material to one bottle at one step in the operation of the feeding means, and means operable at the next step in the operation of the feeding means for simultaneously applying a label to the bottle to which adhesive material has been applied in the previous step and also applying adhesive material to another bottle.

2. In a bottle labeling machine, means for supporting a plurality of bottles, means for feeding the bottles step by step, means for applying adhesive material to one bottle at one step in the operation of the feeding means, means operable at the next step in the operation of the feeding means for simultaneously applying a label to the bottle to which adhesive material has been applied in the previous step and also applying adhesive material to another bottle, and means for moistening the label applied to the bottle.

3. In a bottle labeling machine, means for supporting a plurality of bottles, means for feeding the bottles step by step, means for applying adhesive material to one bottle at one step in the operation of the feeding means, means operable at the next step in the operation of the feeding means for simultaneously applying a label to the bottle to which adhesive material has been applied in the previous step and also applying adhesive material to another bottle, means for moistening the label applied to the bottle, and means for drying the moistened label.

4. In a bottle labeling machine, a shelf for supporting a plurality of bottles, means mounted above the shelf to drag the bottles

in upright position along the shelf, step by step, means for applying adhesive material to one bottle at one step in the operation of the feeding means, means operable at the next step in the operation of the feeding means for simultaneously applying a label to the bottle to which adhesive material has been applied in the previous step and also applying adhesive material to another bottle, and means for drying the label. 75

5. In a bottle labeling machine, a shelf for supporting a plurality of bottles, means mounted above the shelf to drag the bottles in upright position along the shelf, step by step, means for applying adhesive material to one bottle at one step in the operation of the feeding means, means operable at the next step in the operation of the feeding means for simultaneously applying a label to the bottle to which adhesive material has been applied in the previous step, and also applying adhesive material to another bottle, and a heating device operable to dry the label. 30

6. In a bottle labeling machine, means for supporting a plurality of bottles, means for feeding the bottles step by step, means for applying adhesive material to one bottle at one step in the operation of the feeding means, means operable at the next step in the operation of the feeding means for simultaneously applying a label to the bottle to which adhesive material has been applied in the previous step and also applying adhesive material to another bottle, means for heating and trapping air, and means operable to force the trapped air under pressure against the label to dry the same. 95

7. In a bottle labeling machine, means for supporting a plurality of bottles, means for feeding the bottles step by step, means for applying adhesive material to one bottle at one step in the operation of the feeding means, means operable at the next step of operation of the feeding means for simultaneously applying a label to the bottle to which adhesive material has been applied in the previous step and also applying adhesive material to another bottle, and means for supplying air under pressure to the bottle to which the label has been applied. 110 115

8. In a bottle labeling machine, means for supporting a plurality of bottles, means for feeding the bottles step by step, means for applying adhesive material to one bottle at one step in the operation of the feeding means, means operable at the next step of operation of the feeding means for simultaneously applying a label to the bottle to which adhesive material has been applied in the previous step and also applying adhesive material to another bottle, and means for supplying heated air under pressure to the bottle to which the label has been applied. 120 125 130

9. In a bottle labeling machine, means for supporting a bottle, means for applying adhesive material to the bottle, means for applying a label to the bottle after the same has had adhesive material applied thereto, a device for trapping and heating air, and means operable to force the heated air against the label applied to the bottle.
10. In a bottle labeling machine, means for supporting a bottle, means for applying a label to the bottle, a heating device for trapping and heating air, and means operable to force the heated air against the label applied to the bottle.
11. In a bottle labeling machine, means for supporting a bottle, means for applying adhesive material to the bottle, means for applying a label to the bottle, means for moistening the applied label, means for heating and trapping air, and means operable to force the heated air under pressure against the label applied to the bottle.
12. In a bottle labeling machine, means for supporting a bottle, means for applying a label to the bottle, means for trapping and heating air, including two swinging members, normally in co-operative engagement, and means to swing said members out of co-operative engagement and force the heated air against the label applied to the bottle.
13. In a bottle labeling machine, means for movably supporting a bottle, means for applying adhesive material to the bottle, means for moving the bottle after applying adhesive material thereto, means for applying a label to the bottle to which the adhesive material has been previously applied, means whereby the label may be carried by said applying means under the influence of suction and released therefrom in engagement with the bottle under the influence of pressure, and means to trap and heat air and subsequently force the heated air against the label to dry the same after the application of the label to the bottle.
14. In a bottle labeling machine, means for movably supporting a bottle, means for applying adhesive material to the bottle, means for moving the bottle after applying adhesive material thereto, means for applying a label to the bottle to which the adhesive material has been previously applied, means whereby the label may be carried by said applying means under the influence of suction and released therefrom in engagement with the bottle under the influence of pressure, and means subsequently operable to moisten the label on the bottle.
15. In a bottle labeling machine, means for movably supporting a bottle, means for applying adhesive material to the bottle, means for moving the bottle after applying adhesive material thereto, means for applying a label to the bottle to which the adhesive material has been previously applied,
- means whereby the label may be carried by said applying means under the influence of suction and released therefrom in engagement with the bottle under the influence of pressure, means subsequently operable to moisten the label on the bottle, and means to subsequently apply a drying medium to the moistened label to dry the same.
16. In a bottle labeling machine, means for supporting a bottle, means for applying an adhesive substance to the bottle, a label magazine, means operable to carry one label at a time from said magazine to the bottle, and means operable to effect extraction of the label by said carrying means from the magazine and holding the label on said carrying means and operable to effect the release of the label from the carrying means when the label is brought into engagement with the bottle, and a wiper supported on the label magazine operable to wipe over said label carrying means.
17. In a bottle labeling machine, means for supporting a bottle, means for applying an adhesive substance to the bottle, a label magazine, means operable to carry one label at a time from said magazine to the bottle, means operable to effect extraction of the label by said carrying means from the magazine and holding the label on said carrying means and operable to effect the release of the label from the carrying means when the label is brought into engagement with the bottle, and a wiper supported on the magazine operable to wipe over said label carrying means, and means for drying the label.
18. In a bottle labeling machine, means for supporting a bottle, means for applying an adhesive substance to the bottle, a label magazine, means operable to carry one label at a time from said magazine to the bottle, means operable to effect extraction of the label by said carrying means from the magazine and holding the label on said carrying means and operable to effect the release of the label from the carrying means when the label is brought into engagement with the bottle, means for moistening the applied label, and means for drying the same.
19. In a bottle labeling machine, means for supporting a bottle, means for applying an adhesive substance to the bottle, a label magazine, means operable to carry one label at a time from said magazine to the bottle, means operable to effect extraction of the label by said carrying means from the magazine and holding the label on said carrying means and operable to effect the release of the label from the carrying means when the label is brought into engagement with the bottle, means for moistening the applied label, and means for subjecting the applied label to the action of heated air to dry the same.

20. In a bottle labeling machine, means for supporting a bottle, means for applying an adhesive substance to the bottle, a label magazine, means operable to carry one label 5 at a time from said magazine to the bottle, means operable to effect extraction of the label by said carrying means from the magazine and holding the label on said carrying means and operable to effect the release 10 of the label from the carrying means when the label is brought into engagement with the bottle, means for moistening the applied label, and means to subsequently subject the label on the bottle to the action of heated 15 air.

21. In a bottle labeling machine, means for supporting a bottle, means for applying an adhesive substance to the bottle, a label magazine, means operable to carry one label 20 at a time from said magazine to the bottle, means operable to effect extraction of the label by said carrying means from the magazine and holding the label on said carrying 25 means and operable to effect the release of the label from the carrying means when the label is brought into engagement with the bottle, means for moistening the applied label, and means for accumulating and heating air and subjecting the label on the bottle 30 to the action of the heated air under pressure.

22. In a bottle labeling machine, means for supporting a bottle, means for applying an adhesive substance to the bottle, a label 35 magazine, means operable to carry one label at a time from said magazine to the bottle to apply the label to the bottle where adhesive substance has been applied to the latter, a water chamber carried by the label magazine, a wiper carried by the water chamber 40 for movement over said label carrying means, a water magazine, a tubular connection between the water magazine and the water chamber, and means coöperating 45 with the water magazine to apply moisture to the applied label.

23. In a bottle labeling machine, means for supporting a bottle, means for applying an adhesive substance to the bottle, a 50 label magazine, means operable to carry one label at a time from said magazine to the bottle to apply the label to the bottle where adhesive substance has been applied to the latter, a water chamber carried by the label 55 magazine, a wiper carried by the water chamber for movement over said label carrying means, a water magazine, a tubular connection between the water magazine and the water chamber, means coöperating with the 60 water magazine to apply moisture to the applied label, and means for drying the moistened label.

24. In a bottle labeling machine, means for supporting a bottle, means for applying 65 an adhesive substance to the bottle, a label

magazine, means operable to carry one label at a time from said magazine to the bottle to apply the label to the bottle where the adhesive substance has been applied to the latter, a water chamber carried by the label 70 magazine, a wiper carried by the water chamber for movement over said label carrying means, a water magazine, a tubular connection between the water magazine and the water chamber, means coöperating with the 75 water magazine to apply moisture to the applied label, and means for subjecting the applied moistened label to the action of heated air to dry the label.

25. In a bottle labeling machine, means 80 for supporting a bottle, means for applying an adhesive substance to the bottle, a label magazine, means operable to carry one label at a time from said magazine to the bottle to apply the label to the bottle where adhesive substance has been applied to the latter, a water chamber carried by the label magazine, a wiper carried by the water chamber 85 for movement over said label carrying means, a water magazine, a tubular connection between the water magazine and the water chamber, means coöperating with the 90 water magazine to apply moisture to the applied label, and a heating device operable for application to the moistened label 95 to dry the latter.

26. In a bottle labeling machine, means for supporting a bottle, means for applying an adhesive substance to the bottle, a label magazine, means operable to carry one 100 label at a time from said magazine to the bottle to apply the label to the bottle where adhesive substance has been applied to the latter, a water chamber carried by the label magazine, a wiper carried by the water chamber 105 for movement over said label carrying means, a water magazine, a tubular connection between the water magazine and the water chamber, means coöperating with the water magazine to apply moisture to the 110 applied label, means for accumulating and trapping heated air, and means operable to release the trapped heated air against the moistened label to dry the latter.

27. In a bottle labeling machine, means for 115 supporting a bottle, a swingingly mounted label magazine, a swingingly mounted label applying arm coöperating with the magazine to carry a label from the magazine to the bottle and apply the label to the bottle, 120 means for moving said arm out of coöperative relation with the label magazine to take a label from the magazine, means for swinging the label magazine after the extraction of a label therefrom, and means for 125 swinging the label applying arm in a direction opposite to its aforesaid movement after said swinging movement of the label magazine so as to apply the label to the bottle.

28. In a bottle labeling machine, means for supporting a bottle, means for applying adhesive material to the bottle, a label magazine, means to take a label from the magazine and apply it to the bottle at the point where the adhesive material has been applied, means whereby the label may be carried by said label applying means under the influence of suction and released from said label applying means in engagement with the bottle under the influence of pressure, and a wiper slidably carried by the magazine.
29. In a bottle labeling machine, means for supporting a bottle, a swingingly mounted label magazine, a swingingly mounted label applying arm coöperating with the label magazine to carry a label from the magazine to the bottle and apply the label to the bottle, means for swinging the label magazine after the extraction of a label therefrom, means for swinging the label applying arm after said swinging movement of the label magazine, and a wiper to wipe over the label carrying arm.
30. In a bottle labeling machine, means for supporting a bottle, a swingingly mounted label magazine, a swingingly mounted label applying arm coöperating with the label magazine to carry a label from the magazine to the bottle and apply the label to the bottle, means for swinging the label magazine after the extraction of a label therefrom, means for swinging the label applying arm after said swinging movement of the label magazine, and a wiper to wipe over the label carrying arm during swinging movement of the label magazine in one direction.
31. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, and means for swinging the label applying arm after said swinging movement of the label magazine.
32. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, means for swinging the label applying arm after said swinging movement of the label magazine, and a wiper carried by the label magazine to wipe over the label carrying arm during swinging movement of the label magazine in one direction.
33. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, means for swinging the label applying arm after said swinging movement of the label magazine, a water chamber carried by the label magazine, and a wiper carried by the water chamber to wipe over the label carrying arm during swinging movement of the label magazine in one direction.
34. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, means for swinging the label applying arm after said swinging movement of the label magazine, and means for applying a heating medium to the label.
35. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, means for swinging the label applying arm after said swinging movement of the label magazine, a wiper carried by the label magazine to wipe over the label carrying arm during swinging movement of the label magazine in one direction, and means for applying a heating medium to the label.
36. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, means for swinging the label applying arm after said swinging movement of the label magazine, a water chamber carried by the label magazine, a wiper carried by the water chamber to wipe over the label carrying arm during the swinging movement of the label magazine in one direction, and means for applying a heating medium to the label.
37. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label there-

from, means for swinging the label applying arm after said swinging movement of the label magazine, means for moistening the label, and means for subsequently drying the moistened label.

38. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after the extraction of a label therefrom, means for swinging the label applying arm after said swinging movement of the label magazine, a wiper carried by the label magazine to wipe over the label carrying arm during swinging movement of the label magazine in one direction, means for moistening the label, and means for subsequently drying the moistened label.

39. In a bottle labeling machine, means for supporting a bottle, a swingingly mounted labeling magazine, a swingingly mounted label applying arm coöperating with the magazine to carry a label from the magazine to the bottle and apply the label to the bottle, means for swinging the label magazine after extraction of a label therefrom, means for swinging the label applying arm after said swinging movement of the label magazine, a water chamber carried by the label magazine, a wiper carried by the water chamber to wipe over the label carrying arm during the swinging movement of the label magazine in one direction, means for moistening the label, and means for subsequently drying the moistened label.

40. In a bottle labeling machine, means for supporting a bottle, a swingingly mounted magazine positioned normally in a vertical plane and having a mouth at its lower end, a swingingly mounted label applying arm disposed normally in a horizontal plane and provided with a pad at one end for co-operation with the mouth of the magazine and to receive labels thereon from the magazine, means to swing the magazine outwardly to an inclined plane, and means to subsequently swing said arm upwardly into contact with the said bottle.

41. In a bottle labeling machine, means for supporting a bottle, a swingingly mounted magazine disposed normally in a vertical plane and provided with a mouth at its lower end, a swingingly mounted arm disposed normally in a horizontal plane and provided with a pad arranged to receive labels from the magazine through the mouth of the latter, means to swing the magazine toward and away from the pad of said arm, and means to swing said arm into contact with the bottle and back to its horizontal position during the interval of swing of the magazine from said pad back thereto.

42. In a bottle labeling machine, means for supporting a plurality of bottles, a plurality of swingingly mounted magazines, means for connecting the magazines together, a plurality of swingingly mounted arms constructed and arranged to take materials from said magazines, means to swing the magazines from operative to inoperative positions and back to operative positions, and means to swing said arms from normal positions into contact with the bottles to apply the materials taken from the magazines to the bottles and to return said arms back to normal positions during the interval of swing of the magazines from operative positions to inoperative positions and back again to normal positions.

43. In a bottle labeling machine, means for supporting a plurality of bottles, a plurality of swingingly mounted magazines, means for connecting the magazines together, a plurality of swingingly mounted arms constructed and arranged to take materials from said magazines, means to swing the magazines from operative to inoperative positions and back to operative positions, means to swing said arms from normal positions into contact with the bottles to apply the materials taken from the magazines to the bottles and to return said arms back to normal positions during the interval of swing of the magazines from operative positions to inoperative positions and back again to normal positions, a water chamber carried by one of said magazines, and a wiper for feeding water from said chamber and arranged to wipe over one of said arms during swinging movement of the respective magazines.

44. In a bottle labeling machine, means for supporting a plurality of bottles, a plurality of swingingly mounted magazines, means for connecting the magazines together, a plurality of swingingly mounted arms constructed and arranged to take materials from said magazines, means to swing the magazines from operative to inoperative positions and back to operative positions, means to swing said arms from normal positions into contact with the bottles to apply the materials taken from the magazines to the bottles and to return said arms back to normal positions during the interval of swing of the magazines from operative positions to inoperative positions and back again to normal positions, a water chamber carried by one of said magazines, a wiper for feeding water from said chamber and arranged to wipe over one of said arms during swinging movement of the respective magazines, and a tubular connection between said water chamber and one of said magazines.

45. In a bottle labeling machine, means for supporting a bottle, a swingingly mount-

ed label magazine provided with a mouth at its lower end for the passage of labels therefrom, a swingingly mounted arm provided with a pad having air passages and adapted

- 5 to enter the mouth of the magazine, means to swing the magazine, means to swing said arm to carry the pad of the arm from the mouth of the magazine into contact with the bottle, and means to create a suction through
- 10 said pad to withdraw one label at a time through the mouth of the magazine and hold the label on said pad until the latter comes in contact with the bottle, said suction creating means being automatically operable to
- 15 create a pressure through said pad to effect a release of the label from the pad when the label is brought by the pad into contact with the bottle.

46. In a labeling machine, means for supporting a plurality of objects to be labeled, a label magazine, means to apply adhesive substance to the objects, means to take one label at a time from the magazine and apply it over the adhesive substance on the objects,

25 means to supply a moistening medium to the applied labels, and means for drying the labels after the application of moisture thereto.

47. In a labeling machine, means for supporting a plurality of objects to be labeled, a label magazine, means to apply adhesive substance to the objects, means to take one label at a time from the magazine and apply it over the adhesive substance on the objects,

35 means to supply a moistening medium to the applied labels, and means to supply heated air under pressure to the moistened labels.

48. In a labeling machine, means for supporting a plurality of objects to be labeled, a label magazine, means to apply adhesive substance to the objects, means to take one label at a time from the magazine and apply it over the adhesive substance on the objects, means to supply a moistening medium to the applied labels, and a heating device operable to apply heat to the moistened labels to dry the same.

49. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine after

55 the extraction of a label therefrom, means for swinging the label applying arm after said swinging movement of the label maga-

zine, a water chamber, and a wiper carried by the water chamber to wipe over the label carrying arm during swinging movement of 60 the same.

50. In a bottle labeling machine, means for supporting a bottle, a swingingly mounted label magazine, a swingingly mounted label applying arm coöperating with the 65 magazine to carry a label from the magazine to the bottle and apply the label to the bottle, means for swinging the label magazine, means for swinging the label applying arm, and means for wiping the label 70 carrying arm.

51. In a bottle labeling machine, means for supporting a bottle, a swingingly mounted label magazine, a swingingly mounted label applying arm coöperating with the 75 magazine to carry a label from the magazine to the bottle and apply the label to the bottle, means for swinging the label magazine, means for swinging the label applying arm, 80 means for wiping the label carrying arm, and means for moistening the label after its application to the bottle.

52. In a bottle labeling machine, means for supporting a bottle, a swingingly mounted label magazine, a swingingly mounted label applying arm coöperating with the magazine to carry a label from the magazine to the bottle and apply the label to the bottle, means for swinging the label magazine, 90 means for swinging the label applying arm, means for wiping the label carrying arm, means for moistening the label after its application to the bottle, and means for subsequently drying the moistened label.

53. In a bottle labeling machine, means 95 for supporting a bottle, a swingingly mounted magazine provided with a mouth, a swingingly mounted arm provided with a pad arranged to receive substance from the magazine through the mouth of the 100 latter, means to swing the magazine toward and away from the pad of said arm, and means to swing said arm to apply the label, carried by the pad, to the bottle and return the arm to a substantially normal position during the 105 interval of swing of the magazine from said pad back thereto.

In testimony whereof I affix my signature in presence of two witnesses.

GEORGE P. MILLER.

Witnesses:

C. W. FOWLER,
Geo. C. SHOEMAKER.
